United States Patent Office

Des. 184,974
Patented Apr. 28, 1959

184,974

PENCIL SHARPENER STAND OR SIMILAR ARTICLE

Joseph Bacevius, Bridgeport, Conn., and Henry Ruskin,
Bayside, N.Y., assignors to Swingline, Inc., Long Island
City, N.Y., a corporation of New York

Application November 21, 1958, Serial No. 53,465

Term of patent 14 years

(Cl. D74—21)

Fig. 1

Fig. 2

Fig. 3

Fig. 4

Fig. 1 is a front view of a pencil sharpener stand or similar article, showing our new design;

Fig. 2 is a side view thereof;

Fig. 3 is a rear view thereof;

Fig. 4 is a bottom plan view thereof;

Fig. 5 is a top view thereof;

Fig. 6 is a perspective view taken from the rear thereof; and

Fig. 7 is a perspective view taken from the front thereof.

The right side of the pencil sharpener stand or similar article is identical to the left side thereof.

We claim:

The ornamental design for a pencil sharpener stand or similar article, as shown and described.
